(57) **CLAIM**

The ornamental design for a plant shade, as shown and described.

DESCRIPTION

FIG. 1 is a top front right perspective view of a plant shade in accordance with the new design.

FIG. 2 is a front plan view thereof.

FIG. 3 is a left plan view thereof.

FIG. 4 is a rear plan view thereof.

FIG. 5 is a right plan view thereof.

FIG. 6 is a top front right perspective view of a plant shade in accordance with another embodiment of the new design.

FIG. 7 is a front plan view thereof.

FIG. 8 is a left plan view thereof.

FIG. 9 is a rear plan view thereof.

FIG. 10 is a right plan view thereof.

FIG. 11 is a top front right perspective view of a plant shade in accordance with another embodiment of the new design.

FIG. 12 is a front plan view thereof.

FIG. 13 is a left plan view thereof.

FIG. 14 is a rear plan view thereof.

FIG. 15 is a right plan view thereof.

FIG. 16 is a top front right perspective view of a plant shade in accordance with another embodiment of the new design.

FIG. 17 is a front plan view thereof.

FIG. 18 is a left plan view thereof.

FIG. 19 is a rear plan view thereof.

FIG. 20 is a right plan view thereof.

FIG. 21 is a top front right perspective view of a plant shade in accordance with another embodiment of the new design.

FIG. 22 is a front plan view thereof.

FIG. 23 is a left plan view thereof.

FIG. 24 is a rear plan view thereof.

FIG. 25 is a right plan view thereof.

FIG. 26 is a top front right perspective view of a plant shade in accordance with another embodiment of the new design.

FIG. 27 is a front plan view thereof.

FIG. 28 is a left plan view thereof.

FIG. 29 is a rear plan view thereof.

FIG. 30 is a right plan view thereof.

FIG. 31 is a top front right perspective view of a plant shade in accordance with another embodiment of the new design.

FIG. 32 is a front plan view thereof.

FIG. 33 is a left plan view thereof.

FIG. 34 is a rear plan view thereof.

FIG. 35 is a right plan view thereof.

FIG. 36 is a top front right perspective view of a plant shade in accordance with another embodiment of the new design.

FIG. 37 is a front plan view thereof.

FIG. 38 is a left plan view thereof.

(Continued)

FIG. 39 is a rear plan view thereof.

FIG. 40 is a right plan view thereof.

FIG. 41 is a top front right perspective view of a plant shade in accordance with another embodiment of the new design.

FIG. 42 is a front plan view thereof.

FIG. 43 is a left plan view thereof.

FIG. 44 is a rear plan view thereof.

FIG. 45 is a right plan view thereof.

FIG. 46 is a top front right perspective view of a plant shade in accordance with another embodiment of the new design.

FIG. 47 is a front plan view thereof.

FIG. 48 is a left plan view thereof.

FIG. 49 is a rear plan view thereof.

FIG. 50 is a right plan view thereof.

FIG. 51 is a top front right perspective view of a plant shade in accordance with another embodiment of the new design.

FIG. 52 is a front plan view thereof.

FIG. 53 is a left plan view thereof.

FIG. 54 is a rear plan view thereof.

FIG. 55 is a right plan view thereof.

FIG. 56 is a top front right perspective view of a plant shade in accordance with another embodiment of the new design.

FIG. 57 is a front plan view thereof.

FIG. 58 is a left plan view thereof.

FIG. 59 is a rear plan view thereof.

FIG. 60 is a right plan view thereof.

FIG. 61 is a top front right perspective view of a plant shade in accordance with another embodiment of the new design.

FIG. 62 is a front plan view thereof.

FIG. 63 is a left plan view thereof.

FIG. 64 is a rear plan view thereof.

FIG. 65 is a right plan view thereof.

FIG. 66 is a top front right perspective view of a plant shade in accordance with another embodiment of the new design.

FIG. 67 is a front plan view thereof.

FIG. 68 is a left plan view thereof.

FIG. 69 is a rear plan view thereof.

FIG. 70 is a right plan view thereof.

FIG. 71 is a top front right perspective view of a plant shade in accordance with another embodiment of the new design.

FIG. 72 is a front plan view thereof.

FIG. 73 is a left plan view thereof.

FIG. 74 is a rear plan view thereof.

FIG. 75 is a right plan view thereof.

FIG. 76 is a top front right perspective view of a plant shade in accordance with another embodiment of the new design.

FIG. 77 is a front plan view thereof.

FIG. 78 is a left plan view thereof.

FIG. 79 is a rear plan view thereof; and,

FIG. 80 is a right plan view thereof.

The broken lines shown in the drawings illustrate environmental structure and form no part of the claimed design. No claim is made to any top or bottom view, no top or bottom views being shown herein. The break lines having a wavy appearance indicate a symbolic break. The appearance of any portion of the article between the wavy break lines forms no part of the claimed design.
